UNITED STATES PATENT OFFICE.

EGON HASSINGER, OF BARCELONA, SPAIN.

PROPELLING PENCIL.

Application filed March 12, 1923, Serial No. 624,626, and in Spain December 29, 1922.

This invention relates to a pencil holder with magazine for spare leads and it has for its object to construct the pencil in such a manner that the different pieces can be put together exclusively by telescoping and screwing the one into the other without any soldering. The advantage is thus obtained that each part can be easily exchanged when it should get damaged without special work or auxiliary means.

An embodiment of the invention is shown by way of example on the accompanying drawings, in which:

Fig. 1 is a longitudinal sectional view of 15 a part of the outer casing.

Fig. 2 is a longitudinal section of the pencil point and

Fig. 3 a similar section of a sleeve adapted 20 for locking the point.

Fig. 4 shows a longitudinal section of the inner rotatable sleeve.

Fig. 5 is a similar section of a coupling sleeve and

Fig. 6 is a similar section of the actuating 25 cap screwed on the coupling sleeve.

Fig. 7 illustrates in a longitudinal section the intermediate bush.

Fig. 8 is a plan view of the slotted cylindrical piece and washer.

Fig. 9 is a section of Fig. 8.

Fig. 10 is a longitudinal section of the connecting sleeve.

Fig. 11 is a sectional view of the pushing 30 pin and its head.

Fig. 12 shows a sectional side view of a threaded plate.

Fig. 13 shows in plan view the threaded plate inserted into the head.

Fig. 14 is a longitudinal section of an 35 inner threaded sleeve.

Fig. 15 is a longitudinal section of the magazine and cap.

Fig. 16 is a plan view of the magazine.

Fig. 17 is a section of the upper part of 40 the magazine.

Fig. 18 is a section of another form of construction of the cap and

Fig. 19 a plan view of Fig. 18.

Fig. 20 shows the pencil ready for use in 45 longitudinal section.

The improved pencil consists of a casing 1 (Fig. 1) which in the well known manner has a conical forward end 2 and a cylindrical insertion 3 at the point. Into this cylindrical insertion 3 a point 4 is to be inserted which is made from hardened steel and illus-

trated in Fig. 2. The rear end of this point 4 is externally threaded and designed to be screwed into the internally threaded front end of a sleeve 5 (Fig. 3) the rear end 6 of which is conically enlarged. The outer diameter of the enlarged end 6 of sleeve 5 corresponds with the inner diameter of the casing 1. The rear edge of the conically enlarged part 6 of sleeve 5 has incisions 7 for the insertion of a screw driver by means of which the sleeve 5 can be screwed into the rear end of point 4, these two parts being thus securely fixed in the casing 1. The conical enlargement 6 of sleeve 5 serves for guiding the spare leads from the magazine into the position of use. The spare leads are stored in a magazine 7 which is a cylinder made from sheet iron, the outer diameter of the said cylinder corresponding with the inner diameter of the casing 1 so that the magazine having been inserted into the casing 1 from the rear end with slight pressure, it is secured against rotation by the frictional contact with said casing. The pushing pin 8 (Fig. 11) has at its rear end a cylindrical head 9 with transverse slot 10 (Fig. 13). In this transverse slot 10 a cross head 11 is located which is threaded at its outer edges. These outer edges engage with the longitudinal slots 13 of a sleeve 12 (Fig. 4). The threaded cross head 11 is shown in Fig. 12 and its threaded edges engage with the internal threads of a sleeve 14 (Fig. 14). This sleeve has at its rear end a conical collar 15 designed to bear against the upper conical shoulder 16 in a connecting sleeve 17 (Fig. 10). The collar 15 is securely held in its position in the connecting sleeve 17 as shown in Fig. 20 by the forward flange 24 of a centrally bored cylindrical piece 22 (Fig. 9) which is inserted into the annular groove 18 of the rotatable sleeve 12. Against the rear surface of this piece 22 bears the forward edge of an intermediate bush 20 screwed into the internal thread 21 of the connecting sleeve 17. The threaded sleeve 14 is therefore clamped through its collar 15 and the piece 22 between the two sleeves 17 and 20, the collar 19 of the rotatable sleeve 12 engaging loosely in the annular groove 23 of piece 22 so that this rotatable sleeve can freely rotate and consequently feed the threaded cross head 11 and the pushing pin 18 in the fixed internally threaded sleeve 14.

The rotatable sleeve 12 is operated from the outside by means of the cap 25 (Fig. 6).

the internal thread in the neck end of the same being screwed onto a coupling sleeve 27 (Fig. 5). This coupling sleeve 27 has straight inner shoulders 28 designed to come in contact with the straight-lined faces 29 of the rotatable sleeve 12 (Fig. 4). The arrangement of the contact faces 28 and 29 is shown in Figs. 4 and 5 in dash lines.

The several elements of the pencil holder are put together in the following manner:

The steel point 4 is inserted into the outer sleeve 1 in the manner above described and the guide sleeve 5 is screwed on the rear end of said point. The coupling sleeve 27 is placed on the rotatable sleeve 12 so that its contact faces 28 engage with the contact faces 29 of said rotatable sleeve, whereupon the intermediate bush is pushed on so that its forward end bears on the collar 30 of the coupling sleeve 27. In this position the different elements are secured by the insertion of the cylindrical piece 22 into the annular groove 18 of the rotatable sleeve 12. The threaded sleeve 14 is then pushed over the rotatable sleeve 12 and rotated until the threaded cross head 11 of the pushing pin has been screwed into the internal thread of the threaded sleeve. The collar of the threaded sleeve 14 bears on the edge of the cylindrical piece 22. In this position the threaded sleeve is secured by means of the connecting sleeve 17 pushed on and screwed with its internal thread 21 onto the externally threaded forward end of intermediate bushing 20. The cap 25 is then screwed upon the rear end of the coupling sleeve 27 and the elements which are thus securely connected with one another are pushed from the rear into the casing 1 whereupon the pencil holder is ready for use.

Certain constructional details are given by way of example only and may be modified within the limits of the invention. The lower end 31 of the rotatable sleeve 12 is for instance enlarged to receive an eraser.

The space between the threaded sleeve 14 and the magazine 7 serves for storing the reserve leads.

The magazine 7 is closed at the forward end by a rotatable head 33 with an aperture 34 corresponding with an aperture 35 at the forward end of sleeve 7. By the rotation of cap 33 the aperture 34 is made to register with the aperture 35 in the lead reservoir so that a lead can be taken from the reservoir.

The rotation of the rotatable head 33 is limited by a pin 37 of said cap engaging with a slot 36 of the lead magazine 7.

I claim:

1. A magazine pencil all the parts of which are connected with one another without soldering, comprising in combination a casing, a rotatable sleeve having an annular groove at its rear end and longitudinal opposite slits in its forward end, a pushing pin in said rotatable sleeve, a cap closing the rear end of said casing, a coupling sleeve screwed into the front end of said cap, straight inner shoulders in the front end of said coupling sleeve, straight bearing faces on the rear end of said rotatable sleeve, an intermediate sleeve on the rear end of said rotatable sleeve bearing with its rear end on said coupling sleeve, a cylindrical piece on the forward end of said intermediate sleeve engaging with an annular groove of said rotatable sleeve, a slit rear end on said pushing pin and a cross head threadably engaging in said rotatable sleeve and said rear end of said pushing pin and engaging with the internal threads of said threaded sleeve.

2. A pencil holder as claimed in claim 1 comprising in combination with an outer casing tapered at one end, a rotatable sleeve having an annular groove intermediate the ends thereof and longitudinal slits in its forward end, an enlarged head at the other end of said sleeve, a coupling sleeve loosely arranged between said casing and said rotatable sleeve and slidably connected to said rotatable sleeve, a cap screwed on said coupling sleeve for closing and actuating said rotatable sleeve, an intermediate bush inserted between said casing and said rotatable sleeve and having external threads at the forward end, a connecting sleeve screwed on said bush, an inner conical shoulder in said connecting sleeve for clamping purposes, an internally threaded sleeve, a conical collar at the rear end of said threaded sleeve, a cylindrical piece or washer inserted into the annular groove of said rotatable sleeve and adapted to form an abutment against said internally threaded sleeve when clamped by said connecting sleeve, a cross head threadably engaging said threaded sleeve, lateral threaded arms of said cross head passing through the slots of said rotatable sleeve, a pushing pin shiftable in said rotatable sleeve, and a magazine cylinder screwed onto said connecting sleeve and surrounding said threaded sleeve so as to form a space therebetween for spare leads.

In testimony whereof, I affix my signature.

EGON HASSINGER.
